UNITED STATES PATENT OFFICE.

SEARS B. CONDIT, JR., OF BROOKLINE, MASSACHUSETTS, ASSIGNOR TO CONDIT ELECTRICAL MANUFACTURING COMPANY, OF SOUTH BOSTON, MASSACHUSETTS, A CORPORATION OF MASSACHUSETTS.

RENEWABLE ELECTRIC FUSE.

Application filed June 7, 1919. Serial No. 302,516.

To all whom it may concern:

Be it known that I, SEARS B. CONDIT, Jr., a citizen of the United States, and resident of Brookline, in the county of Norfolk and 5 State of Massachusetts, have invented an Improvement in Renewable Electric Fuses, of which the following is a specification.

This invention relates to a renewable electric fuse of the cartridge type.

10 The object of my invention is the provision of a fuse of the type above set forth having a tortuous gas vent through which the heated gas formed upon the blowing of the fuse is expelled, thereby to prevent the 15 destruction of the insulating tubular enclosing casing, and also having means by which the heated gases are cooled previous to their discharge from the fuse thereby to prevent the expulsion of a dangerous flame. 20 Certain features herein shown, but not claimed, are shown and claimed in my pending application Serial No. 302,517, filed June 7, 1919.

Fig. 1 is a side view partly in section, of 25 a renewable fuse embodying my invention.

Fig. 2 is a sectional view of an end cap along lines 2-2 of Fig. 1.

Fig. 3 is a front view of an end cap with the baffle plate removed.

30 Fig. 4 is a front view of the baffle plate. Fig. 5 is a section along lines 5-5 of Fig. 4.

Fig. 6 is a front view of an end ferrule of the fuse casing.

35 Fig. 7 is a front view of the fuse clamping plate.

Fig. 8 is an enlarged sectional view of an end cap taken along its central axis and illustrating more particularly the manner in 40 which the baffle or pressure plate is forced into the end cap.

As here shown, the renewable fuse comprises the tubular casing 10 of suitable insulating material as fiber, having the exteriorly threaded end-ferrules 11 secured on the ends thereof by suitable means, as 45 by pins 12. Said ferrules are formed with end-portions 11^a having arcuate fuse-receiving openings 11^b herein. Said end-portions, 50 at such openings, are formed with the straight edges 11^c over which the ends of the renewable fusible element or strip 13 extended within said tubular casing are adapted to be reflexed. Fuse clamping

plates comprising the discs 14 having slightly less diameter than the end ferrules are adapted to be pressed against the reflexed ends of the fuse strip to force the ends against the end-portions of the ferrules whereby to secure good electrical contact 55 between said fuse and ferrules. Said fuse-engaging plates are formed with raised projections 14^a having the substantially straight lower edges 14^b. Said projections are adapted to be received in the openings 11^b of said 60 ferrules to lock said plates against rotation when the end-caps of the fuse are screwed in place.

The end-caps have the interiorly threaded tubular portions 15 adapted to be removably received upon the exteriorly-threaded end-ferrules of the fuse, and the end-walls 15^a integrally formed with said tubular-portions.

Each of said end-walls has an axial vent 75 16 therein formed as by forcing a suitably shaped tool therethrough and by such operation forming the inwardly directed projection or nozzle 17 through which the vent extends. The cross-section of said vent is 80 gradually enlarged from the tip of said projection to the outer face of the end of the end-cap, as shown.

A baffle-plate 19 comprising the concave or dished disc formed with the flattened central portion 19^a and the outer or peripheral portion 19^b is received in the end cap at the bottom thereof and encloses a space therebetween and the end-wall of the end cap into which said projection 17 extends, but 85 not to such an extent as to contact with said baffle-plate. Said baffle-plate has peripheral notches 19^c through which gas is adapted to pass to be expelled through the vent 16. Said baffle-plate is preferably formed as a 90 member separate from the end cap and of a diameter slightly less than the inner diameter of the end cap whereby it may be received therein. The edge of said baffle-plate is relatively sharp, as indicated at 19^d, 100 and after the plate is in position in the end cap it is struck a blow to imbed its edge in the junction between the tubular portion and the end-wall of the end cap whereby it will be retained in place. When the end cap 105 is screwed onto the end of the fuse the flattened central portion 19^a of the baffle plate is adapted to engage the fuse-engaging

plate 14 thereby to force and hold it firmly against the reflexed end of the fusible element; and it thereby serves as a pressure plate.

- 5 It will be noted that by the arrangement of the baffle-plate the end cap is provided with double end walls and, in connection with the vents, a tortuous passage is provided for the expulsion of gas from the 10 fuse, it being necessary for the gas to flow from the space between the fuse-engaging plate 14 and the baffle-plate through the peripheral passages 19^e therein and then toward the axis of the fuse to be again altered 15 in direction for expulsion through the vent. The fuse-clamping plate also serves to direct the gas from the interior of the fuse casing more or less radially outward into the space between it and the baffle- 20 plate and in itself functions as a baffle-plate to reduce the expulsion velocity of the gas. The fuse-clamping plate, baffle-plate and end cap are made, usually, of copper or copper composition and have a relatively 25 great ability to abstract heat. The heated gas as it is expelled from the fuse is directed into contact with these relatively cold bodies and as a consequence has a considerable portion of its heat removed, so that the gas 30 is relatively cold and thereby without flame when finally expelled from the fuse.

If desirable the space between the baffle-plate and the end-wall of the end cap may contain a porous body 20 as asbestos, steel 35 wool and the like to additionally reduce the expulsion velocity of the gas and at the same time to cool it.

I claim:—

1. A renewable electric fuse of the cartridge type comprising the combination of a tubular enclosing casing, an exteriorly screw-threaded ferrule having an apertured end wall carried by the end of said casing, and an internally screw-threaded end cap 45 having an end wall formed with an aperture therethrough, and a dished pressure plate received in said end cap over the aperture in said end wall and with its periphery in secure frictional engagement with said end cap and having eccentrically disposed gas passages therethrough, said pressure plate arranged to press the end of a fusible element against the end wall of said ferrule. 50
2. An end cap for a renewable electric fuse of the cartridge type having an internally screw-threaded tubular portion, and an end wall having an inwardly directed projection formed with a vent therein, and a dished plate having notches in its periphery and having its periphery in frictional contact with the end cap in a projection-covering position and spaced from said end wall to provide a gas passage from 60 said end wall to provide a gas passage from the notches through said vent.

3. An end cap for a renewable electric fuse of the cartridge type having an internally screw-threaded tubular portion and an end wall having an inwardly directed projection formed with a vent therein, and an apertured dished plate fixed in said tubular portion to enclose said projection and provide a gas passage between it and said vent. 70

4. An end cap for a renewable electric fuse of the cartridge type comprising an interiorly-threaded tubular-portion adapted to be removably received on the end of the fuse, and an end-wall having an axial vent 75 therein, and a baffle-plate comprising a disc arranged in said cap in front of said vent having its peripheral portion embedded in said tubular portion and having notches 80 providing gas passages in its periphery.

5. An end cap for a renewable electric fuse of the cartridge type comprising an interiorly-threaded tubular-portion adapted to be removable received on the fuse, and an end-wall having an axially arranged inwardly directed projection formed with a vent 90 therein, and a concave disc arranged within said cap over said projection having its peripheral portion embedded in said end cap and having peripheral gas passages 95 therethrough.

6. An end cap for a renewable electric fuse of the cartridge type comprising an interiorly-threaded tubular-portion adapted to be removably received on the fuse, and an end-wall having an inwardly directed projection formed with a vent therein, a concave disc arranged within said cap over 100 said projection having its peripheral portion embedded in said end cap and having peripheral notches 105 providing gas passages between it and the tubular portion and a porous body received in the space between said disc and the end-portion of said end cap.

7. An end cap for a renewable electric fuse of the cartridge type having an interiorly threaded tubular portion and an end wall with an axially arranged, inwardly extended projection with a vent opening therein, and a concave disc fixed in said end cap over said projection with its periphery embedded in the junction between said tubular portion and end-wall, said disc having peripheral notches therein forming gas 110 passages from the fuse to the vent opening. 115

8. A renewable enclosed electric fuse of the cartridge type comprising an enclosing tubular casing, exteriorly-threaded end ferrules received thereon having fuse-supporting portions arranged over the ends of the casing with fuse-receiving openings therethrough, a fuse strip extended through said openings having its end portions reflexed over the faces of said fuse-supporting portions, fuse clamping plates engaging the 120 125 130

reflexed ends of said fuse strip, and end caps removably received on said end ferrules having interiorly threaded tubular portions and end walls formed with axially arranged 5 inwardly directed projections having vents therein, and concave discs arranged in said end-caps having their peripheral portions embedded in the junction between the tubular portions and end walls thereof, said discs 10 having peripheral notches providing gas passages from the casing to the vents.

9. In a cartridge fuse an end closure ferrule having its side wall internally threaded at its attaching portion and plain in the

outer portion thereof, a washer located in 15 said unthreaded portion of the ferrule in assembled condition, and a vent opening in the outer end of the ferrule, said vent opening lying within the area defined by the washer.

20

In testimony whereof, I have signed my name to this specification, in the presence of two subscribing witnesses.
